SIGNORS TO OVERMYER MOULD COMPANY, OF WINCHESTER, INDIANA, A CORPORA-
TION OF INDIANA

WORKHOLDING DEVICE

Application filed December 15, 1930. Serial No. 502,485.

Our invention relates to a work holding device for use in connection with a lathe, or other machine, such as a milling machine.

In accordance with our invention, a work holding device is provided, which is adapted to be set for holding the work, and may then have the maximum adjustments, for shifting the work to various positions, without releasing the same. By the use of the device, both time and labor are materially reduced.

The work holding device is adapted to be mounted upon a rotary part or spindle of a lathe, and embodies a plate or disc, which is, preferably, rigidly attached to the rotary part or spindle. A supporting disc or member, is mounted upon the attaching plate, and means are provided for radially adjusting the supporting member with relation to the attaching plate. A rotary supporting member is mounted upon the radially adjustable supporting member, and adapted to be turned with relation thereto. The holding element, or chuck, is carried by the rotary supporting member, and is adapted to be turned with relation thereto, at substantially a right angle to the direction of turning movement of the rotary member. By virtue of the construction of the device, the work may be held within the chuck, which may be adjusted to the selected radial position with respect to the attaching plate, and the work acted upon by a drill, or tool. The rotary supporting member may then be turned for a selected number of degrees, so that the drill may, again, act upon the same side of the work, at a selected point, or points. After one side of the work has been suitably drilled, the holding element may be rotated upon its axis to bring the opposite side of the work adjacent to the drill, so that such opposite side may be acted upon by the drill, in a similar manner. It is, thus, seen that these various operations of the drill upon the work may be effected without the necessity of removing the work from the holding element, thereby effecting a considerable saving in time and labor. The device is of simple construction, is strong and durable.

In the accompanying drawings, forming a

part of this specification, and in which like numerals are employed to designate like parts throughout the same,

Figure 1 is a side elevation of a work holding device embodying my invention,

55

Figure 2 is a similar view of the opposite side of the device,

60

Figure 3 is an end elevation of the device,

Figure 4 is a detailed section taken on line 4-4 of Figure 3,

65

Figure 5 is a longitudinal section taken on line 5-5 of Figure 3,

70

Figure 6 is a plan view of the device,

75

Figure 7 is a front side elevation of the rotary supporting member.

80

In the drawings, wherein, for the purpose of illustration, is shown a preferred embodiment of my invention, the numeral 10 designates the rotary spindle or part of a lathe, or like machine. This spindle is horizontally arranged and disposed in concentric relation to a stationary drill 11, as is well known.

85

The holding device embodies an attaching disc or plate 12, which is, preferably, cylindrical, and has a recess 13, for receiving the forward end of the rotary spindle 10. The attaching disc 12 is rigidly secured to the spindle 10 by bolts 14, or the like.

90

The numeral 15 designates a radially adjustable supporting member, which is, preferably, cylindrical. This supporting member slidably engages the face of the attaching disc 12.

95

As more clearly shown in Figs. 1 and 2, the attaching disc 12 is provided with recesses 16, upon its face, which are shown as horizontal, for the purpose of illustration. These recesses are parallel. The attaching disc 12 is provided inwardly of the recesses 16, with a main recess 17, receiving the inner portion 18 of the radially adjustable supporting member 15. The radially adjustable supporting member 15 has outer portions 19, extending over and beyond the recesses 16. The inner portion 18, of the radially adjustable supporting member 15 is provided upon its edge with horizontal recesses 20, disposed opposite to the recesses 16. The recesses 16 and 20 receive horizontal tracks 21, which are rigidly secured to the attaching disc 12, by bolts 22,

100

or the like, the heads of which are countersunk within recesses formed in the tracks. It is, thus, seen that the recesses 16, recesses 20 and tracks 21, effect a sliding connection 5 between the attaching disc 12 and the supporting member 15, so that the supporting member may be moved radially with respect to the attaching disc. The inner longitudinal edges 23 of the recess 17 are inclined, for slide- 10 able engagement with the inclined faces of wear compensating guides 24, having inner faces 25, which are parallel with the tracks 21, and these faces 25 are parallel with each other. These tapered wear compensating guides are held in the seated position by bolts 26, or the like. It is obvious that the guides 24 may be longitudinally adjusted to compensate for wear, and to effect a proper sliding engagement between the body portion 18, 15 of the radially adjustable supporting member 15, and the attaching disc 12.

Means are provided to move the supporting member 15 radially with relation to the disc 15, including a radially disposed adjusting screw 27, having its outer end rotatably mounted within an opening 28, formed in a lug 29, integral with the disc 12. This screw is rotatable within the lug 29, but cannot move longitudinally with relation thereto. 20

30 The screw-threaded portion of the operating screw engages within a screw-threaded opening formed in a lug 30, integral with the supporting member 15. The screw 27 is provided at its outer end with an extension 31, which 25 is polygonal in cross-section, to be engaged by a tool for turning the same. A disc 32 is carried by the extension 31, to rotate therewith, and this disc is provided with a graduated scale, for co-action with a stationary pointer 33, indicating the extent of movement of the screw.

40 Means are provided to limit the radial movement of the supporting member 15, from the lug 29, so that the operating screw 27 cannot disengage the lug 30. This stop means embodies a block 33', rigidly attached to the disc 12, by a bolt 34', or the like. The block is disposed in the path of travel of a stop element 35', attached to the rotary support- 45 ing member 15, and arranged within a recess 36'.

50 The numeral 34 designates a rotary supporting member, which is, preferably, cylindrical, and has its face or side slidably en- 55 gaging the face or side of the radially adjustable supporting member 15. The rotary supporting member 34 is provided centrally thereof, with a, preferably, tubular cylindrical pivot 35, operating within a bearing 36, arranged within a central opening 37, formed in the member 15. The members 15 and 34 are provided, at their peripheries, with annular recesses 38, receiving the flanges 39 of a coupling ring 40, preferably formed in two 60 parts, and bolted together, as shown at 41.

It is preferred that the coupling ring 40 be held against rotary movement, and to accomplish this, we provide a stop pin 42, which is rigidly attached to the radially adjustable supporting member 15, and arranged to engage faces 43 of the ring parts, as shown. The coupling ring serves to connect the members 15 and 34, at their peripheries, permitting of the member 34 to be turned with respect to the member 15, but holding the member 34 against longitudinal movement from the member 15.

Means are provided to lock the rotary supporting member 34 in the adjusted rotary position, comprising a reciprocating bolt 44, 1000 slidable within an opening 45, formed in the radially adjustable supporting member 15. This bolt is projected by means of a compressible coil spring 46. The bolt 44 has its forward end adapted to enter a bushing 47, arranged within an opening 48, formed in the rotary supporting member 34. The rotary supporting member 34 may have any suitable number of recesses 48, formed therein, spaced apart for any selected number of degrees, such as 180°, or the like. It is, thus, seen that when the rotary supporting member 34 is turned, with respect to the member 15, to the selected position, it is automatically locked in such adjustable position by the bolt 44.

Means are provided to retract the bolt 44, comprising a rotary cylinder 49, operating within a cylindrical recess 50, and held against longitudinal movement by a pin 51, operating within an annular groove 52. This cylinder carries an eccentric pin 53, operating within a transverse slot 54, formed in the bolt. The cylinder 49 has a recess 55, formed at its outer end, which recess is polygonal in cross-section for receiving a suitable tool, for turning the same.

Formed integral with the rotary supporting member 34, and projecting forwardly from the same at its periphery, are spaced parallel arms 56, having cylindrical openings 57 formed therein, receiving bearings or bushings 58. These bushings receive the rotary stub-shafts 59, screw-threaded at their outer ends for receiving nuts 61. The stub-shafts 59 are provided at their inner ends with heads 62, and extend through openings 63, formed in discs 64 and 65. The discs 64 and 65 are locked to the stub-shafts 59, by keys 66. We preferably, arrange wear plates 67 and 68 between the arms 56 and the discs 64 and 65. Formed integral with the discs 64 and 65 is a relatively stationary jaw 69, of a work holding element, disposed opposite to a co-acting adjustable jaw 70. The jaw 70 is connected to the jaw 69, by rods 71, having screw-threaded inner ends 72, engaging within screw-threaded openings 73. The rods 71 have heads 74 rigidly secured thereto, by means of which the rods may be turned. The jaws 130

carry work engaging elements 75 and 76, as shown.

Means are provided to lock the disc 64 in a selected rotary position, comprising a reciprocal bolt 44', identical with the bolt 44, and retracted by the same means. This bolt is adapted to enter recesses 47', formed in the disc 64. The recesses 47' are, preferably, arranged at an angle of 180° apart, although they may be arranged at different distances apart, and any suitable number of recesses 47' may be employed. It is, thus, seen that the work holding element embodying the jaws 69 is adapted to be turned at a right angle to the direction of turning movement of the rotary supporting member 34.

The numeral 77 designates a brake-band, engaging the periphery of the attaching plate 12. One end of this brake-band is connected with a bolt 78, adjustably attached to a lug 79, secured to a portion of the frame 80, of the lathe. The opposite end of the brake-band is connected with a bolt 80 secured to a pivoted lever 81. The brake-band permanently engages the rotary attaching element and normally fits loosely thereon, and by depressing the lever 81, the attaching plate 12 and associated elements may be stopped when the power is cut off from the rotary spindle 10.

The operation of the work holding device as applied to a lathe, is as follows:

The movable jaw 70 is adjusted with respect to the stationary jaw 69, for clamping the work between these jaws. The operating screw 27 is then turned to radially adjust the supporting member 15 to the selected position. The rotary supporting member 34 is now locked in its selected position, and the work holding element is also locked against turning movement, upon its axis. The drill is now brought into engagement with the adjacent side of the work and a hole drilled upon one side of the center of the work. After this is accomplished, the rotary supporting member 34 may be rotated to 180°, and another hole may be drilled in the same side of the work, upon the opposite side of its center and at the same distance. By arranging the recesses 47 at different distances apart, and employing them in different numbers, any suitable number of openings may be drilled about the center of the work, at selected points. It is obvious that other holes may be drilled in the same side of the work by a further adjustment of the operating screw 27. After the drilling operation has been completed upon this side of the work, the work holding element is turned upon its axis for 180°, bringing the opposite side of the work adjacent to the drill, whereby the same drill operation may be repeated upon the opposite side of the work, if desired. The invention is not restricted to the

turning of the work holding element for a distance of 180°, as it may be turned throughout any selected distance, and locked in the adjusted position. It is, thus, seen that the various operations described can be quickly 70 and conveniently performed without removing the work from the work holding element.

It is to be understood that the form of our invention herein shown and described is to be taken as a preferred example of the same, and that various changes in the shape, size and arrangement of parts may be resorted to without departing from the spirit of my invention, or the scope of the subjoined claims.

Having thus described our invention, what we claim is:

1. A work holding device comprising an attaching plate, a supporting member provided with a central opening and having a recess in its periphery, said supporting member slidably engaging the face of the attaching plate, means to radially adjust the supporting member with relation to the plate, a rotary supporting member having a central pivot to enter the central opening of the 85 radially adjustable supporting member, and provided at its periphery with a recess, a coupling ring having flanges to enter the recesses at the peripheries of said members, means to lock the rotary supporting member to the 90 radially adjustable supporting member, at a selected adjusted rotary position, and work holding means carried by the rotary supporting member.

2. A work holding device, comprising an 100 attaching plate, a supporting member provided with a central opening and having a recess in its periphery, said supporting member being movable radially with relation to the attaching plate, means to radially adjust the supporting member with relation to the plate, a rotary supporting member having a central pivot to enter the central opening of the radial adjustable supporting member and provided at its periphery with a 105 recess, a coupling ring having flanges to enter the recesses at the peripheries of said members, means carried by the radially adjustable supporting member to engage the coupling ring and hold it against rotation 110 with relation to the radially adjustable supporting member, means to lock the rotary supporting member to the radially adjustable supporting member at a selected adjusted rotary position, and work holding means carried by the rotary supporting member.

3. A work holding device comprising an attaching plate, a supporting member arranged at one side of the attaching plate and adjustable radially with relation thereto and provided in its periphery with an annular recess, means to radially adjust the supporting member with relation to the plate, a rotary supporting member disposed upon one side of the radially adjustable supporting 130

- member and provided in its periphery with an annular recess, a two-part coupling ring having flanges to enter the recesses at the peripheries of said members, means to lock the rotary supporting member to the radially adjustable supporting member at a selected adjusted rotary position, and work holding means carried by the rotary supporting member.
- 10 4. A work holding device, comprising an attaching plate, an annular supporting member having a central opening and having an annular recess in its periphery and arranged upon one side of the attaching plate, said annular supporting member being provided with a lug having a screw-threaded opening and being provided substantially diametrically opposite the lug and adjacent to its periphery with a recess, a radially adjusting screw carried by the attaching plate and engaging within the screw-threaded opening of the lug to adjust the annular supporting member radially of the attaching plate, a stop element secured to the attaching plate and arranged to enter the last-named recess formed in the annular supporting member to engage therewith and limit its radial movement in one direction, a rotary supporting member having a central pivot to enter the central opening of the annular supporting member and provided in its periphery with an annular recess, a coupling ring having flanges to enter the recesses at the peripheries of said members, means to lock the rotary supporting member to the radially adjustable supporting member at selected rotary positions, and work holding means carried by the rotary supporting member.
- 20 5. A work holding device, comprising an attaching plate, a supporting member having an annular recess in its periphery and arranged upon one side of the attaching plate, sliding connecting means between the attaching plate and supporting member so that the supporting member may be adjusted radially with relation to the attaching plate, means to effect the radial adjustment of the supporting member, a rotary supporting member disposed upon one side of the radially adjustable supporting member and provided in its periphery with an annular recess, a coupling ring having flanges to enter the annular recesses at the peripheries of said members, means to lock the rotary supporting member to the radially adjustable supporting member at a selected adjusted rotary position, a pair of spaced arms rigidly secured to the rotary supporting member and projecting beyond one side of the same, said arms being provided at their free ends with discs having flat faces, a pair of discs arranged inwardly of and adjacent to the first-named disc and having co-acting flat faces, means to pivotally connect the inner discs with the outer discs so that they are free to
- 25 30 35 40 45 50 55 60 65

turn at substantially a right angle to the direction of adjusted turning movement of the rotary supporting member, spring-pressed bolts to lock the inner discs to the outer discs at selected adjusted positions, a relatively stationary jaw rigidly connecting the inner discs, an opposed movable jaw, and adjustable means connecting the movable jaw with the relatively stationary jaw near the ends of said jaws.

In testimony whereof we affix our signatures.

MORTON LONGNECKER.
WILLIAM M. ELKINS.
